UNITED STATES PATENT OFFICE.

WILLIAM R. ISAACS, OF THOMPSONVILLE, ILLINOIS, ASSIGNOR OF ONE-HALF TO
THOMAS G. PUCKETT, OF THOMPSONVILLE, ILLINOIS.

RAILROAD APPLIANCE.

1,078,287.

Specification of Letters Patent.

Patented Nov. 11, 1913.

Application filed August 27, 1913. Serial No. 786,947.

To all whom it may concern:

Be it known that I, WILLIAM R. ISAACS, a citizen of the United States, residing at Thompsonville, in the county of Franklin 5 and State of Illinois, have invented certain new and useful Improvements in Railroad Appliances, of which the following is a specification, reference being had to the accompanying drawings:

- 10 This invention relates to certain improvements in railroad appliances and has relation more particularly to a device of this general character particularly designed and adapted for use in connection with rails, 15 and an object of the invention is to provide a device of this type of a simple and comparatively inexpensive nature having novel and improved means whereby proper alinement of a rail may be effected.
- 20 The invention also consists in the details of construction and in the novel arrangement and combination of the several parts of my improved device whereby the same is rendered simpler, less expensive and other- 25 wise better adapted and more convenient for use, all as will hereinafter be more fully set forth.

The novel features of my invention will be carefully defined in the accompanying 30 claims.

In order that my invention may be better understood, I will now proceed to describe the same with reference to the accompanying drawings forming part of this specification and wherein—

Figure 1 is a view in elevation of an appliance constructed in accordance with an embodiment of my invention and in operative position, the rail being shown in section; Fig. 2 is a view in front elevation of the device set forth in Fig. 1; Fig. 3 is a detail view in top plan of the rail engaging means as herein disclosed; and Fig. 4 is a detail perspective view illustrating one of the side plates as herein employed.

As shown in the accompanying drawings, 1 denotes a base member of any ordinary or preferred configuration or material but as herein shown is substantially of rectangular 50 form and has secured substantially at the transverse center thereof the longitudinally directed rack member 3 of a predetermined length. While this rack member may be carried by the base 1 in any manner as will

operate with facility, I find it of particular 55 advantage that the same be held in operative position through the medium of a plurality of fastening devices 4^a such as rivets or the like whereby it will be readily observed that such rack member 3 can be readily and conveniently replaced should the same become undesirable for use from any cause.

Upwardly directed from the longitudinal side portions of the base member 1 are the side plates 2 having intermediate their 65 lengths the elongated slots 4 disposed in alinement and arranged in a vertical plane intersecting the horizontal plane occupied by the rack member 3 for purposes which will hereinafter be obvious. While these 70 side plates 2 may be secured to the base member 1 in any desired manner, I find the structure as disclosed in the drawings to possess the greater efficiency and wherein each of such side plates 2 are provided with 75 the inwardly directed flange or lip 5 adapted to overlap the adjacent longitudinal edge portion of the base member 1 and adapted to be secured thereto by the rivets 6 or the like. The slots 4 serve as bearings for the 80 transversely directed shaft member 7 to which is affixed a disk member 8 provided with a segmental rack 9 adapted to mesh with the rack member 3 and such disk 8 is also provided at a predetermined point with 85 a conventional socket 10 adapted to accommodate an end portion of a manipulating handle or lever 11 whereby a convenient and effective means is afforded for imparting 90 rotary movement to the disk member 8 as is believed to be clearly apparent.

12 indicates the rail engaging member and as herein disclosed includes a hook portion 14 adapted to be engaged with the base flange 15^a of the rail 15, as shown in Fig. 1, 95 while the opposite end of such member 12 is bifurcated as indicated at 16, in order to straddle or bridge the disk member 8, the stems of the bifurcation 16 being provided with alining apertures 17 through which 100 passes the shaft member 7.

When in applied or operative position, the base member 1 and its intimate parts are adapted to be held stationary. This may be accomplished in any manner as will 105 operate with facility but I found it of particular advantage to provide the base 1 with an angularly extended portion 18 adapted to

serve as a convenient anchoring means as is believed to be obvious to those skilled in the art to which my present invention appertains and which is believed to be clearly apparent from the drawings. When the disk member 8 is caused, through proper manipulation of the lever or handle member 11, to rotate in the direction of the arrow *a*, the axis of such disk member will 10 be shifted through the coaction of the rack member 3 and the segmental rack 9 which will result in such strain or pull upon the rail 16 as to affect the proper adjustment or alinement thereof, it being obvious that 15 the extent of movement of the axis of the disk member 8 will depend upon the extent of adjustment required by the rail.

From the foregoing description of my improvements it will be obvious that a railway appliance constructed in accordance 20 with my invention is of a simple and comparatively inexpensive nature and is particularly well adapted for use by reason of the convenience and facility with which 25 it may be applied in operative position and by reason of the convenience of its operation, and it will also be obvious that my improved railway appliance is susceptible of some change without material departure 30 from the principles and scope of the invention and for this reason I do not wish to be understood as limiting myself to the precise formation and arrangement of the several parts as herein set forth in carrying 35 out my invention in practice.

Having thus fully described my inven-

tion what I desire to claim and secure by Letters Patent is:

1. A device of the character described comprising a base member provided with a rack, a shaft carried by the base member and capable of adjustment relatively thereto, a disk mounted on the shaft and provided with a segmental rack adapted to engage the rack of the base, means for rotating the disk, and track engaging means carried by the shaft.

2. A device of the character described comprising a base member having a rack, side plates carried by the base and provided with elongated openings, a shaft mounted within the elongated openings of the side plates, a disk fixed to the shaft and having a segmental rack adapted to engage the rack of the base member, means for rotating the disk, and a track engaging device carried by the shaft.

3. A device of the character described comprising a base having a rack, a shaft carried by the base and capable of adjustment relatively thereto, a disk carried by the shaft and provided with a segmental rack adapted to engage the rack of the base, track engaging means carried by the shaft and straddling the disk, and means for rotating the disk.

In testimony whereof I hereunto affix my signature in the presence of two witnesses.

WILLIAM R. ISAACS.

Witnesses:

W. A. SIMMONS,
J. S. HARRIS.
